UNITED STATES PATENT OFFICE.

WILLIAM H. KOEHLER, OF CLEVELAND, OHIO, ASSIGNOR OF TWO-THIRDS
TO L. C. GUNTHER AND JONATHAN FARROW, OF SAME PLACE.

CASH-CARRIER.

SPECIFICATION forming part of Letters Patent No. 374,683, dated December 13, 1887.

Application filed January 28, 1887. Serial No. 225,823. (No model.)

To all whom it may concern:

Be it known that I, WILLIAM H. KOEHLER, a citizen of the United States, residing at Cleveland, in the county of Cuyahoga and State of Ohio, have invented an Improvement in Cash-Carriers, of which the following is a specification.

My invention relates to a cash-carrying apparatus, and is more particularly related to the manner of imparting motion to the carriage.

In the accompanying drawings, Figure 1 shows a side view of part of my propelling device and the frame supporting the same. Fig. 2 is a side view of the carriage, also showing one end of cylinder and flanges. Fig. 3 is an end view of the carriage.

Having reference to the figures and lettered part of drawings, A is a suspension-rod, the upper end of which is securely fastened to the ceiling, with the lower end fastened into frame A'.

B is a double conical pulley set upon a shaft, the ends of which revolve in suitable journals.

D is a shaft having spiral flanges *d* set upon a surface and extending from one end along two-thirds (more or less) of the length of shaft, which is secured in frame A', and revolves in journals *a*, and having pulley B' at a point suitably situated between the journals *a*.

B' is a pulley set upon shaft D, to which is permanently fixed one end of strap C. The other end of strap C is fastened to pulley B by a pin or screw, *g*. C is another strap or band, the upper end of which is fastened to the opposite side of the apex of the conical pulley B. To the lower end of the same is fastened handle E.

F is a guide-rod fastened to the frame at *f*, and is sharpened at one end.

J is a hollow cylinder, which is suspended from the wire or rod O by means of pulley M, to which it is fastened by screws *m*.

From the inner surface, and at each end of same, are set two beveled flanges, N, being in line with one another and opposite each other, and having the bevel of each slanting in opposite directions.

On the upper and outer surface of J are stened guides L, provided with rubber or

other suitable cushions, *l*, to overcome inertia, and also provided with suitable holes to allow of the free passage of the wire O. K is also another guide fastened to the upper and outer surface of J, and near the center of same, with its upper part shaped into a hollow cylinder, K'. The ends of the said hollow cylinder are beveled, as shown by dotted lines *k*, so as to more readily engage the pointed end of rod F. K is also provided with a suitable hole so situated as to allow of the free and easy passage of the wire O.

G is a case, which is firmly fastened at its upper end to the lower outer surface of cylinder J by means of screws, and provided on the inner surface with suitable notches to engage the springs I.

H is the cash-box, provided with two or more springs I, and fits easily into the case G, and is held in place by means of springs I, as described.

At each end of wire O is the frame A', provided with screw D', rod F, pulleys B and B', with attachments situated as before described.

To operate my device, we will suppose the carriage to be at rest—that is to say, the cylinder J is pierced by the screw D' and K' is pierced by the rod F. The hand of the operator is laid upon E, and gives the same a downward pull. This revolves pulleys B and B' by means of straps C and C', so as to give the shaft D and screw D' a rotary motion. The spiral flanges *d* engage flanges N, the result of which is to throw the cylinder J forward and off of the screw D' and rod F by means of the centrifugal force thereby imparted.

What I claim as new, and desire to obtain Letters Patent for, is—

1. In a cash-carrier, a device for imparting motion, a shaft, D, having spiral flanges *d* set upon the surface of the same, so as to form screw D', and provided with pulley B', and journaled upon frame A' at *a*, in combination with straps C C' and double conical pulley B, all fastened, supported, and operated as shown and described, and for the purpose set forth.

2. In a cash-carrying carriage, the hollow cylinder J, provided at each end with two flanges, N, set opposite each other and in line with one another, the flanges being beveled,

as shown and described, all combined for the purpose herein fully set forth.

3. In a cash-carrying apparatus, the screw D' upon shaft D, provided with pulley B', and strap C, fastened, as shown, to the conical pulley B, and strap C' and rod F, in combination with the carriage having cylinder J, pro-

vided with flanges N, pulleys M, and wire or rod O, as shown and described, and for the purpose set forth.

WM. H. KOEHLER.
